UNITED STATES PATENT OFFICE.

LEWIE W. HARDAGE, OF NASHVILLE, TENNESSEE.

COMBINED HIP AND SPINE PAD.

Application filed July 7, 1926. Serial No. 120,951.

This invention relates to new and useful improvements in combined hip and spine pads for football players.

Amongst the several objects of the invention are to provide a pneumatic pad which will protect both the hips and spine from injuries due to impacts; to provide such a pad from moisture-proof material whereby moisture or perspiration will not be absorbed by the material and whereby the weight of the pad will not thereby be increased; to provide such a pad of simple construction whereby the same may be readily applied to the person or removed therefrom, and to provide a plate of relatively stiff material in cooperative position relative to the outer faces of the pad sections and at points adjacent the hips, to better protect the wearer from impacts and to also assist in distributing the force of the impact throughout the inflated sections of the pad.

With these and other objects in view which will more fully appear the nature of the invention will be more clearly understood by the following description, the appended claims, and the several views illustrated in the accompanying drawings, in which—

Figure 1 is a perspective view showing the application of my invention to a pair of football trousers,

Figure 2 is a plan view of one of the pad sections embodying my invention,

Figure 3 is a horizontal sectional view therethrough,

Figure 4 is an enlarged detailed sectional view showing the air inlet tube and the protecting flaps therefor,

Figure 5 is a plan view of one of the plates of relatively stiff material, and

Figure 6 is an enlarged vertical sectional view showing the relation between the pad, the waist portion of the football trousers, and the plate of relatively stiff material.

Like numerals designate corresponding parts throughout the several figures of the drawings.

Referring to the accompanying drawings, A designates a pair of football trousers which include the usual leg portions 5—5 and waist portion 6.

Associated with the football trousers is a pneumatic waist encircling pad B which is adapted to have its lower end positioned within the waist portion 6 of the trousers and to serve as a protector for the hips and spine of the wearer.

The pad B is formed by two complementary sections 7—7. Each section is formed from two superposed sheets 8—8 of non-porous material, preferably including rubber as a base. The marginal edge portions of these sheets are sealed, preferably by vulcanizing. The sealed edge portions include longitudinal or vertically extending front and rear edge portions 9 and 10 respectively, 60 a top edge portion 11 and a bottom edge portion 12. The sheets are also sealed, preferably by vulcanizing, at spaced points to form resultant air channels 13, 14, 15, 16, 17, 18, 19, 20, 21, 22, 23 and 24, the points of sealing or vulcanization being respectively indicated by the numerals 25, 26, 27, 28, 29, 30, 31, 32, 33, 34 and 35, said points preferably extending in parallel lines and in parallelism with the vertical edge portions 9 and 10. 70 The sealed points, or lines 25 to 35 inclusive, terminate at their upper and lower ends in spaced relation to the upper and lower marginal edge portions 11 and 12 to form laterally extending air channels 36 and 37 which serve to provide open communication between the air channels 13 to 24 inclusive. 75

In order to inflate these sections, I have provided a valve 38. This valve is preferably located at the upper end of the air channel 24 and is formed from a rubber tube. After the pad has been inflated, the end portion of the tube may be rebent and tied so as to effectively close the valve. In order to protect the valve, the sheets 8 are 80 formed with upwardly extending ears 39—39 which are disposed on opposite sides of said valve.

In order to attach the sections 7—7 and to secure the entirety to the wearer, I have provided the rear vertical edge portion 10 of each section with a plurality of eyelets 40 and the front vertical edge portion 9 of each section with a plurality of eyelets 41. A lace 42 is associated with the eyelets 40 95 for securing the rear edge portions 10 of the sections in overlapping relation and a lace 43 is associated with the eyelets 41 for securing the front edge portions 9 in overlapping relation. 100

The lower forward portion of each section is cut away as at 44 to give freedom of leg movement of the wearer, particularly when running. The rear portion of each section is also cut away as at 45 to give freedom 110 of leg movement to the wearer and at the same time to give sufficient length to the rear

portions of the sections to properly protect the spine.

In order to further protect the hips of the wearer from injury, I have positioned a plate 46 against the outer face of the associated section 7 and at a point which covers the hip. This plate 46 is of relatively stiff material and is preferably formed of fibre board. In order to support the plate in proper relation, I have attached the same to the inside face of the waist portion 6 of the trousers by means of a cloth cover 47 which is stitched to the waist portion 6 by means of stitches 48. The lower rear portion of the plate 46 is cut away as at 49 to give clearance for leg movement of the wearer, particularly when running.

It will, therefore, be seen that when my improved pad has been properly positioned and inflated, any impact directed against either hip will be distributed by reason of the relatively stiff plate 46 throughout a large number of the inflated air channels of the pad. It will also be observed that by reason of the air channels being vertically disposed, the pad may be readily encircled about the waist and hips of the wearer.

It is of course to be understood that the details of structure and arrangements of parts may be variously changed and modified without departing from the spirit and scope of my invention.

I claim:

1. In a football suit, the combination with a pair of trousers having a waist portion adapted to extend over the hips of the wearer, and a waist encircling protector overlapping the waist portion of the trousers and including cushioning means cover-

ing the hips of the wearer, and a plate of stiff material disposed against the outer face of the cushioning means for distributing the force of impact throughout said means.

2. In a football suit, the combination with a pair of trousers having a waist portion adapted to extend over the hips of the wearer, and a waist encircling protector overlapping the waist portion of the trousers and including pneumatic cushioning means covering the hips of the wearer, and a plate of stiff material disposed against the outer face of said pneumatic cushioning means for distributing the force of impact throughout said means, said plate being secured to the waist portion of the trousers.

3. In a football suit, the combination with a pair of trousers having a waist portion adapted to extend over the hips of the wearer, a waist encircling protector overlapping the waist portion of the trousers and including pneumatic cushioning means covering the hips of the wearer, said protector comprising superposed sheets of non-porous material, said sheets being sealed along their marginal edge portions and also provided with a plurality of sealing points intermediate said marginal edge portions to form resultant communicating air channels, a valve air inlet communicating with one of said channels, and a plate of stiff material disposed against the outer face of said pneumatic cushion for distributing the force of impact throughout said cushion, said plate being attached to the waist portion of the trousers.

In testimony whereof, I have hereunto subscribed my name.

LEWIE W. HARDAGE.
